SCISSORS SHARPENER AND STONE HOLDER

Reuben Shelley Decker, Dycusburg, Ky.

Application February 15, 1937, Serial No. 125,910

6 Claims. (Cl. 51—214)

The invention aims primarily to provide a new and improved device of simple and inexpensive nature for conveniently holding an abrasive stone and accurately guiding scissors blades while 5 sharpening them upon said stone.

A further aim is to so construct the device that it may be effectively used for holding the stone in various convenient positions for sharpening knives and other edged tools without danger 10 of cutting the hands.

While I refer above to an abrasive stone, the invention may be used in connection with a file instead of a stone if desired.

With the above objects in view, the invention resides in the novel subject matter hereinafter described and claimed, description being accomplished by reference to the accompanying drawing.

Fig. 1 is a perspective view showing the manner in which the device is used when sharpening 20 scissors.

Fig. 2 is a vertical sectional view on line 2—2 of Fig. 1.

Fig. 3 is an end elevation illustrating another 25 manner in which the stone may be held for sharpening edged tools.

Fig. 4 is a side elevation showing still another of the various ways in which the stone may be held.

Fig. 5 is a plan view illustrating a file instead 30 of a stone, held by the device.

A preferred construction has been illustrated and will be specifically described, with the understanding, however, that variations may be 35 made within the scope of the invention as claimed.

The numerals 6 on the drawing denote two flat elongated jaw plates each having a free longitudinal front edge 7 and each provided with 40 a central handle 8 integral with and projecting rearwardly from its rear edge. The two plates are pivotally connected with each other and moved toward each other by means of a C-shaped spring 9 having slots 10 through which the handles 8 pass, the edges of said spring being hooked over suitable ribs 11 on said plates.

Both ends of each plate 6 are bent laterally outward in the same direction to provide flanges 12, each flange of each plate being at an obtuse angle to said plate. The outer edges 13 of the flanges 12 are preferably straight as shown, and the front edges 14 of said flanges are also preferably straight, these edges being free or exposed and being disposed in the same plane with the front edge 7. The outer front corner of each

flange 12 is provided with a lug 15 projecting forwardly beyond the edge 14.

When a stone S is positioned between the plates 6 in the manner shown in Figs. 1 and 2, the outer edges 13 of two of the flanges 12 will 5 rest solidly upon any suitable supporting surface to support the device and the stone in position to sharpen scissors, using either of the uppermost of the flanges 12 as a guide along which to slide the blade B while sharpening its edge upon the 10 stone. The free ends of the handles 8 are preferably so positioned with respect to the flanges 12 that when either pair of these flanges rests upon a supporting surface, the lowermost handle 15 will also rest on said surface, whereby the handle assists the flanges materially in rigidly supporting the device and the stone.

When the stone is to be held with one of its flat sides entirely exposed as seen in Fig. 3, said stone may be so positioned that it rests 20 against the front edges 7 of the plates 6 and the front edges 14 of the flanges 12, the edges of the stone being then gripped by the lugs 15. With the stone and the holding device thus connected, said holding device may be readily held 25 in one hand while the other hand is used for sharpening a knife or other edged tool upon the stone. Also, with the stone held as shown in Fig. 3, either edge of said stone may be used for sharpening a scissors blade, using one or 30 another of the lugs 15 and the contiguous portion of the flange 12 as a guide for the blade, and by thus using the edge of the stone, no channel will be worn in either flat face of said 35 stone to interfere with sharpening other tools.

If any sharpening operation may be more conveniently performed by holding the stone in an inclined position with one of its edges disposed upwardly as seen in Fig. 4, the holder may be readily engaged with said stone as illustrated in 40 this view, the holder and the lower corner of the stone then resting on a suitable supporting surface.

If desired, the device may be used in connection with a file F (Fig. 5) instead of with a 45 stone, principally for sharpening scissors, the scissors blade being guided in the same manner as explained in connection with Fig. 1. If it be desired to slightly corrugate the cutting edge of 50 either blade of the scissors, said edge may be rested lengthwise upon one side of the file and firmly pushed transversely of said file, in the direction taken by the cutting edges E of said file.

It will be seen from the foregoing that a novel 55

device has been provided for carrying out the objects of the invention, and while the details disclosed are preferable, attention is again invited to the possibility of making variations with-
5 in the scope of the invention as claimed. Moreover, it will be understood that the device may be constructed in numerous sizes for coaction with stones of different sizes.

I claim:—

- 10 1. A device of the class described comprising two flat elongated spring-closed jaw plates to lie against opposite sides of an abrasive stone, said plates having free longitudinal front edges and being provided with handles projecting rearwardly from their rear edges for use in spreading said plates apart, both ends of one of said plates being bent laterally outward to provide transverse flanges, the outer edges of said flanges being shaped to rest on a flat surface to support the device and the stone.
- 15 2. A device of the class described comprising two flat elongated spring-closed jaw plates to lie against opposite sides of an abrasive stone, said plates having free longitudinal front edges and being provided with handles projecting rearwardly from their rear edges for use in spreading said plates apart, both ends of one of said plates being bent laterally outward at an obtuse angle to constitute a guide against which to slide a scissors blade while sharpening the edge thereof upon the stone.
- 20 3. A device of the class described comprising two flat elongated spring-closed jaw plates to lie against opposite sides of an abrasive stone, said plates having free longitudinal front edges and being provided with handles projecting rearwardly from their rear edges, both ends of one of said plates being bent laterally outward at an obtuse angle to constitute a guide against which to slide a scissors blade while sharpening the edge thereof upon the stone.
- 25 4. A device of the class described comprising two flat elongated spring-closed jaw plates to lie against opposite sides of an abrasive stone, said plates having free longitudinal front edges and being provided with handles projecting rearwardly from their rear edges, both ends of one of said plates being bent laterally outward to provide transverse flanges, the outer edges of said flanges being shaped to rest on a flat surface to support the device and the stone.
- 30 5. A device of the class described comprising two flat elongated spring-closed jaw plates to lie against opposite sides of an abrasive stone, said plates having free longitudinal front edges and being provided with handles projecting rearwardly from their rear edges, both ends of one of said plates being bent laterally outward to provide transverse flanges, the outer edges of said flanges and the rear end of one of said handles being relatively positioned to jointly rest on a flat surface to support the entire device and the stone.
- 35 6. A device of the class described comprising two elongated jaw plates and means for moving them toward each other, said jaw plates having free front longitudinal edges for disposition at one side of an abrasive stone, said plates being both bent laterally outward at their ends to provide lateral flanges, said lateral flanges having free front edges to abut said one side of the stone, said flanges being also provided with lugs projecting beyond said free front edges thereof to engage the edges of the stone to grip the latter, at least one of said lugs and the flange carrying the same being obliquely positioned to guide a scissors blade while sharpening the edge of this blade upon an edge of the stone.

REUBEN SHELLEY DECKER.

apart, both ends of each plate being bent laterally outward to provide flanges, said flanges having free front edges to abut said one side of the stone, said flanges being also provided with lugs projecting beyond said free front edges 5 thereof to engage the edges of the stone to grip the latter.

4. A device of the class described comprising two flat elongated spring-closed jaw plates to lie against opposite sides of an abrasive stone, said plates having free longitudinal front edges and being provided with handles projecting rearwardly from their rear edges for use in spreading said plates apart, both ends of one of said plates being bent laterally outward to provide transverse 15 flanges, the outer edges of said flanges being shaped to rest on a flat surface to support the device and the stone.

5. A device of the class described comprising two flat elongated spring-closed jaw plates to lie 20 against opposite sides of an abrasive stone, said plates having free longitudinal front edges and being provided with handles projecting rearwardly from their rear edges, both ends of one of said plates being bent laterally outward to 25 provide transverse flanges, the outer edges of said flanges and the rear end of one of said handles being relatively positioned to jointly rest on a flat surface to support the entire device and the stone.

6. A device of the class described comprising two elongated jaw plates and means for moving them toward each other, said jaw plates having free front longitudinal edges for disposition at one side of an abrasive stone, said plates being 35 both bent laterally outward at their ends to provide lateral flanges, said lateral flanges having free front edges to abut said one side of the stone, said flanges being also provided with lugs projecting beyond said free front edges thereof to engage the edges of the stone to grip the latter, at least one of said lugs and the flange carrying the same being obliquely positioned to guide a scissors blade while sharpening the edge of this blade upon an edge of the stone.
